UNITED STATES PATENT OFFICE.

JAMES H. WARD, JR., OF BUCHANAN, MICHIGAN, ASSIGNOR TO JAMES H. WARD & SON, INC., OF BUCHANAN, MICHIGAN, A CORPORATION OF MICHIGAN.

DESIGN FOR A MAIL-BOX DOOR.

Application filed January 27, 1927. Serial No. 20,519. Term of patent 3½ years.

To all whom it may concern:

Be it known that I, JAMES H. WARD, JR., a citizen of the United States, residing at Buchanan, in the county of Berrien and State of Michigan, have invented a new, original, and ornamental Design for Mail-Box Door, of which the following is a specification, reference being had to the accompanying drawing, forming part thereof.

The figure is a front elevational view of a mail box door showing my new design.

I claim:

The ornamental design for a mail box door, as shown.

JAMES H. WARD, JR.
